UNITED STATES PATENT OFFICE.

ROBERT DAVIS, OF BROOKLYN, NEW YORK, ASSIGNOR TO ELCO SHOE MANUFACTURERS, INC., OF BROOKLYN, NEW YORK, A CORPORATION OF NEW YORK.

SHANK STIFFENER.

Application filed May 6, 1926. Serial No. 107,160.

This invention relates to a shank stiffener or arch member which is made of leather and which is connected to the outer sole of a boot or shoe so as to support the arch and heel of a foot.

The invention is designed to provide a leather arch member with a pad having substantially flat sides and located beneath the heel of the arch member, in order to give rigidity above the pad to the arch member and to obviate any permanent deformation thereof which may be caused by imperfect or protuberant surfaces on the heel of the foot.

It is well-known, that when a shoe is worn by a person with a calloused heel, that the leather of the sole underneath the calloused portion gradually becomes concaved or hollowed causing discomfort to the foot. It is also known that the constant pounding of the heel of a heavy person on the rear of the stiffener of the shoe causes it to prematurely lose its shape; in other words it stretches transversely causing the upper to widen and the rear portion of the shoe becomes loose when worn a short time thereby sliding up and down.

It is the object of the present invention to provide a leather stiffener by means of which the heel portion of the shoe is strengthened, the thickness of the leather stiffener being gradually increased from the toe of the shoe to the heel thereof thereby stiffening the member where the stress is greatest.

Another object of the invention is to provide the leather member with a side extension whereby the arch of the foot is supported and any movement of the member in the shoe is eliminated.

Another object of the invention is to provide the leather member with means to permit greater ease of transverse flexure at the forward part in advance of the metatarsal bones of the foot, thus permitting a rocking motion from the heel to the forward end of the member when the foot is in action.

The invention resides more particularly in the novel combinations hereinafter described and claimed, reference being made to the accompanying drawing, in which:

Fig. 1 represents a vertical section of a shoe embodying this invention.

Fig. 2 is a bottom perspective view of the shank stiffener.

In the drawing is shown a resilient leather member consisting of a heel portion 5 and having a forward cut-out portion 6 forming bifurcated ends 7 with side notches 8 to permit transverse flexure at the forward portion of the member. On the underside of the member a spring steel shank 9 is affixed to stiffen the member. The leather member is also provided with a side extension 10 adapted to fit into the inner side of the arch portion of a shoe. The leather member tapers from its forward end to the rear and its greatest thickness is at the heel portion thereof which is subjected to the greatest stress.

On the underside of the heel portion of the leather member, a rigid pad 12 made of fibre or leather board having a flat upper and under side is fastened by means of nails 11. The outline of pad 12 is substantially the same as the tread of the heel of a shoe. The pad can be waterproofed with paraffin or other oily or wax-like substance to eliminate squeaking after the leather dries. When the foot is in motion it constantly flexes the forward part of the leather member thereby giving more equal distribution of the weight or applied force.

The outline of the leather member is shaped to snugly fit into a shoe which consists of a sole 14 and an upper 15 sewed to the sole as is well-known. The leather member extends from the heel to the front end of the arch and its forward portion is skived so as to produce a smooth joint free of ridges. The leather member is preferably arranged on the sole of a turned shoe or pump but it will be understood that it can be located in a welt shoe. The leather member is fastened to the sole by nailing or cementing it into position and it is covered by a thin leather lining 16 glued or otherwise secured to the sole and upper.

In the above construction the rigidity of the pad keeps part of the leather arch member adjacent thereto in a flat condition and it compensates for any irregular growth on or defects in the heel of a foot. It has been found by experiment that when the leather member is placed in a turned pump it is unnecessary to cement or fasten it to the sole, inasmuch as the pad is fitted in a recessed part of the sole, which will prevent it from moving out of place or shifting in the shoe.

The rear portion of the leather arch mem-

ber is preferably fastened to the sole of the shoe by means of nails 17 passing into the heel. These nails prevent the leather member from lifting when the cement is loosened 5 by perspiration or otherwise. In order to stiffen the member under the arch and at the same time secure it to the sole a pair of rivets or staples 18 inserted in holes 19 are utilized, and they prevent lifting or loosening 10 of the leather member adjacent its line of flexure.

I claim:—

1. A shank stiffener for a shoe comprising a bendable leather member having an arch 15 portion and a heel portion, the said heel portion having a relatively rigid pad connected to the underside thereof, the said pad being shorter and narrower than the said heel portion, the arch portion of the said member 20 having a resilient stiffening member connected thereto, the adjacent ends of the said stiffening member and of the said pad being

spaced from each other, the said pad having a substantially flat surface adjacent the said bendable member and having sufficient rigidity to maintain said substantially flat surface under normal use. 25

2. A shank stiffener for a shoe comprising a bendable leather member having an arch portion and a heel portion, the said heel portion having a relatively rigid pad connected to the underside thereof, the arch portion of the said member having a resilient stiffening member connected thereto, the adjacent ends 30 of said stiffening member and of the said pad being spaced from each other, the said pad having a substantially flat surface adjacent the said bendable member and having sufficient rigidity to maintain said substantially flat surface under normal use. 35 40

In testimony whereof I have hereunto set my hand.

ROBERT DAVIS.
